UNITED STATES PATENT OFFICE.

FELIX BENEDICT HERZOG, OF NEW YORK, N. Y.; HENRIETTA HERZOG EXECUTRIX OF
SAID FELIX BENEDICT HERZOG, DECEASED.

ELECTRIC SIGNALING APPARATUS AND CIRCUITS.

1,028,089.

Specification of Letters Patent. Patented May 28, 1912.

Application filed November 8, 1893. Serial No. 490,105.

To all whom it may concern:

Be it known that I, FELIX BENEDICT Herzog, Ph. D., a citizen of the United States, and a resident of the city, county, and State 5 of New York, have invented a new and useful Improvement in Electric Signaling Apparatus and Circuits, of which the following is a specification.

My invention, in its fullest embodiment, 10 consists in means for signaling from various floors of a building to two or more elevators in such a manner that the conductor of each car is informed whether the waiting passenger wishes to go up or down, and also 15 whether any other conductor has answered the call, and it also enables each conductor to signal to the waiting passenger that such conductor is about to respond to the indication, and also enables each conductor to indicate to the other conductors.

In the drawings Figure 1 is a rear view of the operating parts of the calling box at the stations or floors; Fig. 2 is a side section, and Fig. 3 a front view of the same. Fig. 4 is 25 a general diagram of the circuit arrangements and the general organization of the system. Fig. 5, a similar diagram, the individual circuits being multiplied as they would be in a system using four buttons. 30 Fig. 6 is a detail of the "short-circuiting" bell of the well known type, and Fig. 7 shows details of the box shown in Figs. 1 and 2.

Referring to the figures in detail:—In 35 Figs. 1, 2, and 3, a duplicate arrangement is shown; the parts of the "Up" and "Down" buttons, respectively being similar. The corresponding parts on the lower box bear the same letters as those on the upper but 40 have a prime added thereto. In the description a part will be mentioned either with or without the prime according to which view of the part referred to is most easy to find. By pushing either button part H fixed to 45 shank P is brought into contact with the contact spring F, which normally rests in position against an insulated pin, O. Fixed to the shank is the cam with two ends, the one end H, preferably making the contact 50 with F when it is not convenient to have this made directly by the shank P, and the second end X acting to lock the button in its depressed position whenever a current 55 through magnet M holds the armature E against the poles. The armature or an extension shows through the window in the front plate in such a manner that its position or its changes of position may be observed from the front of the box. In the "Up" part of the box the armature falls 60 upon the poles when the cam is pushed aside, whereas in the "Down" part a suitable spring K helps the magnet in raising the armature. The circuit within the box is from the metal parts (including the frame 65 A and shank P with its cam H), and out to the common wire by means of the metal case and base shown in section in Fig. 2. These parts are common to both push buttons in any box, and in all of the boxes they 70 are common to the general feed wire 19 (shown in heavy lines). The other feed wire or pole connects to this first wire by the respective individual or floor wires— 75 shown in multiple in Fig. 5,—there being one of these for each button, and these end— 80 for each button—on top of the insulated stud T' for the down and T for the up calls (Fig. 2) thence go to spring C' (or C), magnet, and contact spring F where the circuit is completed when that particular button is pushed. Spring C is fixed to an insulated block arranged in any suitable manner. In Fig. 7 the shape of spring F is 85 changed so as to make the illustration clearer. The individual wire for each button ends in a spring F after passing through its magnet; hence, when the button is pressed and current is in line, a contact is 90 made at F and current through the magnet 95 will cause the armature to stick to the poles of M and will thus cause the button to continue the contact until circuit is broken at the distant station, whereupon the armature permits the spring S to restore the button 100 contact. The manner of producing this break will be described hereafter. The spring C which is fixed to a suitable insulated block seen in Fig. 1, serves to cause contact with T—the line wire terminal—when the box is fastened to its base, thus permitting of rapid unfastening and inspection of parts and re-connection when box is fastened by the suitable devices shown. The box thus

described is used on each floor of the building, in a position easily accessible to those about to enter the elevators.

Fig. 4 shows in one form of diagram, and Fig. 5 in another form of diagram how the system as a whole is set up in a building with two elevators arranged side by side; in Fig. 4 only two boxes are shown, although there would be a box for each floor, and the circuit is shown as connecting two cars although it may be led to as many cars as desired. The apparatus in the upper right-hand corner represents the devices in one car (supposed to be near the top of the building at the moment chosen for illustration) while the lower figure represents the devices in the second car. In Fig. 5 the devices of the respective cars are arranged vertically, the small circle representing the junction of the lines to each car. The cars are connected together by cables in any suitable manner—as here shown—in a series arrangement, the flexible cable which connects each car apparatus to the shaft work being typified in Fig. 4. The apparatus in each car would usually comprise the attention device or bell, 10, (10' in the upper car) this being common to the rest of the apparatus in each car, inasmuch as it is the general return circuit (heavy line) and in addition to this bell the system comprises indicating appliances to locate the floor, these appliances consisting of an annunciator, composed of a number of similar parts; only one of each part being shown herein for each car, thus simplifying the illustration; it being understood that there would ordinarily be as many of these as there are buttons in the system, as shown in Fig. 5. A generator, 16, feeds the common wire, 19, and the individual wires connected to each button are energized when the contacts are made as above. The circuit leads through as many cars as may be desired, and if desired, an indication (as for instance by short-circuiting bell 10) is given whenever the circuit is closed by the depression of one of the buttons, and continues until all buttons are restored from the cars. This bell is short-circuiting (as shown in Fig. 6) because if an ordinary trembler were used its own breaks would immediately deenergize the magnet of the depressed button instead of permitting this to remain energized until one of the conductors answers the call. In each car, for each button at each floor or station is an individual indicator, thus collectively making an annunciator, but only one is shown in each car in Fig. 4, and four in Fig. 5, it being understood that all are alike. In the lower car this is shown as a magnet, 12, attracting an armature whose change of position may be observed—while in the other car it is shown as an incandescent electric lamp. As

already stated the circuit which was closed by the operation of pushing a button on a floor continues closed until it is broken at some point beyond. This break may be produced by various devices, including a separate switch for each car, or, preferably, a separate switch for every indication or button (as 14—15 in Fig. 5), although one controller in the common wire would answer, but not always as well, because whenever this would be operated all of the energized buttons would be restored, instead of one only. If the sparking due to the break of the circuit is too great, a suitable resistance, 13, is used, and the separation of contacts 14—15 will throw in this resistance, thus weakening the current enough to cause magnet M, at the operated station, to let the armature be pushed back by the slope of the cam at the button. In Fig. 4 the circles 17—17' represent junction boxes to which the flexible cables are fastened. As a result of the arrangement shown the effect of the depression of a button by any waiting passenger will be to close the circuit at that button, whereupon the circuit will be completed and current will flow from the generator 16 to line 20 and leg 18 to the metal back plate to which the box is fixed, thence to the box frame and the metal shank of button P, its extension and the spring F (with which it is brought in contact by the act of depression of the push button), thence to the magnet, and through it to the automatic contact formed by the stud and spring T. C., and thence into the individual or floor wire corresponding to that particular button, and thence into the first car. From the point where it enters the car the current flows first through the two terminals of the cut-out switch (these normally short-circuiting the resistance, 13, if such resistance has been used) thence into the individual indicating devices (either magnet or lamp as the case may be) thence out into the next car, where it passes through similar parts, thence back to the return wire and into the attention call or bell, 10', of the car just referred to, thence back in series into a similar device in the first car, and so back to the current supply. Any number of such series can be arranged in parallel between the two mains to the current supply, their connection with the first main being at the respective buttons on the floors; whereas their connection with the second main would all be at the annunciator which is referred to below. It is evident that for convenience the individual wires of each set will be bound together into some form of cable, which would necessarily be made up in a manner to be sufficiently flexible to permit of its following the cars during their rise and fall. The various indicating devices it will be observed are preferably as here

shown, of a character in which the indication continues only as long as the current flows, and are automatically restored upon the cessation of the flow; thus in the case of 5 the magnetic form, 12, the armature is attracted to the magnet upon closure of the circuit at the button, and continues attracted until restored, (by the spring indicated, or else by gravity, as it would be in the position shown) as soon as the current is interrupted or sufficiently weakened; and in the case of the lamp the glow would begin, continue and cease under like conditions. It is evident that with sufficient current any 10 number of such indicators would indicate simultaneously, provided their respective circuits were closed, and the bells would evidently continue to sound, no matter whether only one or all of the corresponding 15 circuits were energized. The individual indicators of each car are preferably grouped together so as to form as an aggregate an annunciator, and suitable indication marks in proximity to each will indicate 20 to the operator which button it was that has been depressed and consequently which floor has signaled. In each annunciator indicators corresponding to a given button should be located in a similar position and the corresponding 25 cut-out switches should for convenience be placed in close proximity to the indicator of the line to which they belong.

It is obvious that in the form selected for illustration every indicator in series on a 30 wire will operate simultaneously, and therefore every conductor would simultaneously know that a given button had been pushed; for instance, the button on the 6th floor marked to indicate that a passenger wished 35 to be taken up. But it is not necessary that all conductors should respond, and the conductor whose car would be in a position which would make it proper that he should be the next to take a passenger under those 40 conditions would therefore ordinarily be the only proper one to respond, whereas the conductor or conductors of the other car or cars, although they would know that a call had been sent from that point by a passenger 45 wishing to go in that direction, would disregard it unless they had reason to believe that the conductor whose duty it was was not in a position to perform that duty, or had neglected it. In other words—it is, of 50 course, obvious that there is no intention of having more than one car stop to take one passenger who has signaled from a given floor, the intention being to secure as the final result of the operation of the organization 55 as a whole, and by which all the cars receive the signal, that which is set forth in the printed instructions to the waiting passenger which are ordinarily displayed on the front of the floor box in the manner 60 shown in the illustration—"The first car

that passes in the direction indicated will stop for you." By giving the required information simultaneously to all cars the result is secured that if the first car about to 65 pass in the desired direction should not be available for any reason, as, for instance, should be moving at such speed as not to be able to stop in time, or should be too full, the next car could respond and thus the passenger can give the effective notice in connection with a group of cars, by the act of 70 operating one signal only as against the necessity of operating one for each car as it existed before my invention.

During the entire time that the indication corresponding to any floor is thus displayed in the cars, the corresponding button remains held in place as the result of the magnetic clutch described. The proper conductor as soon as he wishes 75 to respond gives a tap upon the button of the cut-out switch, 14, thus opening the circuit, whereupon three distinct effects are produced:—first, the indicator corresponding to that particular line is restored 80 to its normal condition (no matter how many other indications may be showing from other floors at the time); second, the "answer back" or return signal is given to the passenger by the mechanical click 85 which he hears as his button is returned to its normal position under stress of the spiral spring S on the shank (and at the same time the shutter is displayed as indicated on the directions in Fig. 3); third, the corresponding 90 indication disappears in the other car or cars, thus indicating to the other conductors that there is no longer need for them to pay attention to that particular call.

It will be noticed, from the construction 95 of the push button box parts, that the act of pushing the button results electrically in the contact between the piece H and the spring F, and also mechanically in permitting the approach of the armature to the 100 poles of the magnet (by gravity in the case of a magnet placed as the "Up" button is placed, and by the aid of the spring K where the armature naturally falls away from the magnet, as in the "Down" button.) This 105 approach in either case is due to the fact that the inclination of the cam X is such that as the button returns to its normal position, under stress of the helical spring S, the slope of the cam will force up the armature 110 while rocking it upon the pivot which supports it in the frame as shown. This particular motion is of course not essential to the 115 general function of the box, nor is the particular form of box or push button controller which is shown essential to the operation 120 of the invention but this special form has been illustrated and selected in the present embodiment of the invention because of the simple mechanism required to make it 125 130

possible for a very small amount of current to produce the clutching effects upon the closure of the circuit, and while this continues. The greater attraction of the magnet for the armature when the latter is close to the pole will make it possible for a current to hold the armature down in spite of the force exerted upon it laterally by the cam, whereas the same current could not possibly 5 energize the magnet sufficiently to enable the attraction upon the armature to cause the latter to depress the button. It is obvious, that when a passenger who has pushed a button, desires to cancel the call, 10 he merely pulls out the button (the flange of which prevents it from sinking beyond his reach) and, as merely the slight magnetic attraction and the friction of the cam hold it in, a barely perceptible pull will 15 restore the button contact and the normal circuit conditions.

The general organization shown as applied to elevator signals is broadly new among other points in that it provides means 20 for signaling by the single act of depressing one button in an installation having several cars, so that, as stated in the wording of the floor box in Fig. 3 "the first car that passes in the direction indicated, will 25 stop;" further, that such signals may be given to more than one car simultaneously; further, that such signals may be given for "up" and "down" directions; further, that signals can be given from the car to the other 30 cars, or to the floor, or both; further, that when desired more than one car can give such return signals; further, that the circuit control which produces the signals just referred to may in the alternative or jointly 35 be used for purely circuit controlling purposes, as for instance the deenergization of a magnet at the floor box which this particular organization requires, and which deenergization is by itself not the signal, but is a distinct 40 electro-mechanical effect.

From another point of view the novelty broadly consists in having an annunciator, each of the individual parts of which is, by suitable circuit connections, connected to a 45 corresponding circuit controlling point at one or more other stations, and may be restored from such other station or stations, and such restoration may also take place where desired in the alternative in the station at which it is located. Among specific 50 points of novelty of the elements, some particular features of the circuit-closing device have already been pointed out, and among others is the feature of the lamp control 55 from either of several distant stations; and further, such lamps arranged as an annunciator, with the controlling points for the corresponding lamps at each of two or more points, these points being aggregated for 60 ready control by one operator for each group

of such points. The mention of these various points of novelty is merely by way of illustration, and it is by no means exhaustive. Many modifications may be made.

My invention also comprises the use of 70 this circuit-controlling button without an elevator connection, and comprises also the use of several annunciators with means of restoring the drops from other points.

It also comprises other features shown. 75

I do not herein claim broadly as an independent device the various subcombinations or the general organization of a combined circuit controller magnet or magnets and adjuncts of the general form or nature shown in the floor box, as this is made the subject of a pending application S. N. 317,869, filed July 12, 1889; and all the claims which were herein prior to the elimination for purposes of division called for by the office under the rules and which relate to such an independent controller, when used alone, are limited to the form in which the normal conditions are restored as the result of a weakening of the attraction of the 80 armature. 85

The term "multiple" in the claims is not intended to limit the invention to uses where the signal is given to several cars simultaneously, or is simultaneously restored in or as to several cars, but is merely a convenient term equally applicable to variations in which cars successively receive it, or one car only receives it because of its priority or otherwise; the sole requirement being that more than one car is used in the general organization and that its stopping is controlled from a single signal as a new departure from the heretofore usual arrangement by which there would be as many floor buttons as cars, and each button was limited in its effect to its control over its own car. 90 95 100 105

I claim:

1. At each of several floors of a building apparatus constructed and arranged both to control a signal in an elevator car and to be responsive to control from the elevator car; and in the car a signal and means for affecting the responsive floor apparatus, substantially as described. 110 115

2. In an elevator signal system an up and a separate down call on a floor, and a separate answer back on each floor for each call, together with connections leading to a distant point through which connections the 120 answer back is operated; a signal on the car responsive to the calls, and means for simultaneously terminating the signal and operating the answer-back from the car.

3. An annunciator comprising a group of 125 indicators, each of which is separately controlled from a distance, together with means operated at the annunciator and adapted to control an answering signal to correspond with each of the indicators, and correspond- 130

ing to each indicator an answer back device which acts to so respond, and simultaneously to restore the corresponding indicator and none other.

5. 4. A multiple car elevator signaling system comprising a separate up and down device for giving signals from each floor, receiving devices constructed, located and arranged to specify to the operator of each of 10 several cars which of the floor devices has been operated, separate wires from each of the floor devices to a common point for controlling said receiving devices, a common source of current and as many switching 15 devices as there are cars, each constructed, arranged and operable to modify the normal reception of signals for another car, these elements so coöperating that normally any car may receive any signal but that 20 such reception may be dependent upon the operation of the switch corresponding to another car.

5. 5. A multiple car, elevator signal system comprising a floor call and means whereby 25 it indicates in more than one car; an answer-back at the floor associated with one or more of the cars; means for operating the answer back or return signal, combined with means adapted to cause the operation of the answer 30 back to affect the subsequent relation between the floor call and the indicators for the other cars.

6. A multiple car elevator signal system comprising a floor call and in two or more 35 of these cars a signal controllable thereby, and in one or more of these cars, a restoring device, constructed and connected to affect the restoration of the normal condition in another car.

40. 7. An annunciator at a receiving station comprising a lamp for each indication, means and devices at each of several sending stations for initiating the lighting of the corresponding lamps as signals from 45 such stations, means for continuing this lighting after such initiation by the operator at the corresponding sending station, and means, controllable at the annunciator station separately for each lamp, and constructed, adapted and arranged to restore the lamp to its original condition, together with circuit connections including a current supply common to the lamp and to the corresponding signal sending device at the sending station.

8. A multiple car, elevator signal system comprising a floor call on each floor, an indicating device for each of two or more cars, and connections between the floor call of a 50 floor and each of the indicating devices; together with a switch and connections in a car constructed and arranged so that when operated the switch will terminate the operation of the floor call.

65. 9. A multiple car elevator signal system,

comprising a calling device on each floor, in each of two or more cars, a car signal and at some suitable point a switch for controlling the corresponding signal, together with connections between the floor call of a floor 70 and each of the car signals.

10. A normally unenergized signaling system comprising the combination of a circuit controller at one station, indicators at two or more distant stations, and connections whereby said indicators are simultaneously operated by the actuation of the controller, means for continuing this operation after the cessation of the act of the operator who has initiated it, together with switches 75 at each of the distant stations, each constructed, connected and operable to contribute in the restoration of the indicators at both stations.

11. The combination of circuit controllers 85 at several signaling stations, and at each of two or more distant receiving stations, an annunciator with an independent element corresponding to each of the circuit controllers, together with independent switch 90 elements at each receiving station, and connections whereby at either receiving station any operated annunciator element thereat as well as the corresponding element at the other station may be simultaneously 95 restored.

12. In electric signaling apparatus for elevators, the combination with two series of individual electric lamps, one series serving for "up" signal purposes and the other 100 series serving for "down" signal purposes and both grouped within the car, electric circuits wherein said lamps are placed, said circuits comprising individual wires leading to the corresponding individual lamps, a source of current common to said individual lamp circuits, circuit controlling mechanism for the passenger upon the floors of the building whereby current is caused to pass through said lamps, and suitable 110 means including for each lamp a device whereby the passage of current through said lamps may be broken.

13. A multiple car elevator signal system comprising for a floor a circuit closer constructed to operate as a first or initiating element, a car signal controllable thereby together with suitable circuit connections; a magnet coöperating normally as a second operative element in the control of the signal; combined with a switch in the car constructed and arranged to be operated by the conductor thereof to prevent the normal operation of the car signal when he actuates it.

14. A multiple car elevator signal system comprising a signal controlling instrument on a floor; a car signal normally controllable thereby, a magnetic switching device contributing normally as an intermediate 130

- element in the production of the signal, together with suitable circuit connections; combined with a switch in the car arranged to be operated by the conductor thereof 5 and acting to prevent the normal operation of the car signal, the switch being constructed to return automatically to its normal condition after such operation.
15. A multiple car elevator signal system 10 comprising a floor instrument including a pair of normally separated contacts, means for closing these at will, a magnet and armature adjusted and arranged to coöperate in keeping them joined; and a circuit loop normally closed through the magnet after the floor instrument has been actuated together with a pair of normally closed contacts for each car in the loop, and means whereby any pair may be opened to control the magnet.
16. A multiple car elevator signal system 15 comprising a floor instrument including a pair of normally separated contacts, means for closing these at will, a magnet and armature adjusted and arranged to coöperate in keeping them joined while energized; and a circuit loop normally closed through the magnet after the floor instrument has been actuated together with a pair of normally closed contacts for each car in the loop, and means whereby any pair may be opened to control the magnet by deenergizing it.
17. A multiple car elevator signal system 20 comprising a circuit controlling device for a floor; a controllable device in each car; as many restoration controlling devices as there are cars and magnetically controlled adjuncts constructed and arranged to be controlled by the actuation of any of the restoration controlling devices and to contribute in the termination of the control started by the actuation of the circuit controlling device; together with suitable circuit connections.
18. In a circuit controlling system, a magnet and in circuit therewith a circuit controlling terminal manually operable and also controllable thereby; several independent switching devices and a connection from the magnet thereto, each operable during the normal condition of the other to control the magnet to cause it to restore the said terminal to its normal condition.
19. A multiple car elevator signal system, comprising an actuating device, normally open contacts arranged so that they may be manually joined by a signaling operator as the first step in the operation of signaling, a magnetically controlled element controlled thereby arranged to produce a further effect in the operation; as many restoration controlling devices as there are cars—said devices being located at different points and 60 each constructed and arranged to be oper- 65 able independently of any other and to terminate the signal by controlling the said element.
20. A multiple car elevator signal system comprising for each floor an instrument comprising a normally separated pair of contacts, constructed and arranged to be joined, and at and for each such floor an answer-back device responsive to a restoration control from each of as many points as there are cars; a car signal constructed and arranged to be controllable by the floor instrument of a floor, and as many restoration controlling devices as there are cars; together with suitable circuit connections, all arranged so that any one of the said restoration controlling devices may be made to coöperate with the said "answer-back" device and the said car signal.
21. A multiple car elevator signaling system, comprising for each floor an instrument comprising a normally separated pair of contacts, constructed and arranged to be joined, circuit connections and adjuncts including a magnet constructed and arranged so that a change in current conditions initiated by the junction of said contacts will continue thereafter; in each car an annunciator comprising an element for each floor instrument: a common element 95 constructed and arranged to respond in common to the operation of any of the independent elements and to continue in operation as long as any remains operated; together with means for causing any annunciator element to be controlled independently from any car.
22. In a signaling system a circuit closer at each of several sub-stations; separate lines from these to a central station, at the central station an annunciator with a separate element for each such line; and at each of one or more other points a separate switching device for each such element together with means including suitable circuit connections whereby the corresponding annunciator element may be restored to its normal condition by the operation of any of the corresponding switching devices.
23. In a signaling system a circuit closer at each of several sub-stations; separate lines from the stations to an annunciator station fitted with a lamp directly within each such line; a magnet constructed and arranged to control the continued operation of the corresponding lamp; and at each of one or more other points a switching device corresponding to each lamp and constructed and arranged to control the extinguishing of a lighted lamp from either 110 of such distant points.
24. In a signaling system a circuit closer at each of several sub-stations; separate lines from the stations to an annunciator station fitted with a lamp directly within 115

each such line; a magnet constructed and arranged to control the continued operation of the corresponding lamp; and at each of one or more other points a switching device corresponding to each lamp and constructed and arranged to control the extinguishing of a lighted lamp from either of such distant points; together with a signaling device operated in common for 10 all the lamps.

25. In a signaling system a circuit closer at each of several sub-stations; separate lines from the stations to an annunciator station fitted up with a lamp directly within each such line; a magnet constructed and arranged to control the continued operation of the corresponding lamp; and at each of one or more other points a switching device corresponding to each lamp and constructed 15 and arranged to control the extinguishing of a lighted lamp from either of such distant points; together with a signaling device operated in common for all the lamps and constructed and arranged to continue 20 until all have been extinguished.

26. A signaling system comprising a number of lamps in series on one line and a switch corresponding to and located near each lamp; a magnet contributing in the 30 continuation of the lighting of the lamps after the lighting has been initiated, and means arranged to initially light and to extinguish said lamps; either of the said switches being adapted to extinguish all the 35 lamps.

27. A multiple car elevator signal system, comprising a call device on a floor; in a car a signal device controllable by the call; circuit connections for the signal device in 40 the car; a magnet constructed and arranged to contribute in restoring the original conditions after the signal has been given, together with controlling switches—equal in number to the cars and suitably organized 45 and connected so that the actuation of either will control the magnet in the restoration.

28. A multiple car elevator signaling system comprising a signaling instrument on a floor; in a car a signal device controllable 50 by the instrument; circuit connections for the signal device in the car; a magnetically controlled device arranged to contribute in restoring the original conditions after the signal has been given; together with a separately movable device associated with each 55 car, each constructed and adapted to operate with the magnetically controlled device in the restoration.

29. A multiple car elevator signal system, comprising in each of several cars, an annunciator comprising a lamp for each of several floors; on each floor an instrument comprising means for controlling the lighting of the corresponding lamp in all of the 60 cars simultaneously; suitable circuit con- 65

nections; means for continuing the operation of a lamp after the cessation of the preliminary control and devices equal in number to the cars all constructed and arranged and adapted so that either may contribute 70 in the restoration of lamps corresponding to that floor to their normal condition.

30. A multiple car elevator signaling system comprising, in each of several cars, an annunciator comprising a lamp for each 75 floor; on each floor an instrument comprising means for controlling the lighting of the corresponding lamp in all the cars simultaneously; a magnet corresponding to each such instrument constructed and arranged to contribute in the continuation of the control over the operation of the lamps; suitable circuit connections, and a set of contacts corresponding to each set of lamps representing such floor instruments, all the 80 contacts being constructed, arranged and adapted so that either may control the magnet in the extinguishment of the set of lamps.

31. A multiple car elevator signaling system comprising in each of the several cars an annunciator comprising a lamp for each 90 floor; on each floor an instrument comprising means constructed and connected so that the passenger may effect the initial control 95 of the corresponding lamp in all the cars simultaneously; a magnet constructed and arranged to coöperate with suitable circuit connections to contribute in the continuation of the operation of the lamps, and 100 a device not included in the floor instrument and constructed and arranged to be actuated to extinguish all the lamps of a set.

32. A multiple car elevator signaling system, comprising a circuit closer on each 105 floor for the up call and a separate closer for the down call; and in each of several cars an annunciator with a separate element corresponding to each call; means, including suitable connections whereby all of the 110 corresponding annunciator elements are operated simultaneously when a floor call is operated and means for causing their simultaneous restorations; said means including one or more devices distinct from the circuit closer on the floor.

33. A multiple car elevator signal system comprising a push-button closer on each floor, a lamp corresponding to each closer in each of several cars, and in each car an 115 audible device, including a magnet constructed, arranged and adapted to sound simultaneously with the lighting of any of the lamps of that car.

34. In electric signaling apparatus for 125 elevators, the combination with two series of individual annunciating devices, one series serving for "up" signal purposes and the other series serving for "down" signal purposes and both grouped within the car, 130

electric circuits wherein said devices are placed, said circuit comprising individual wires leading to the corresponding individual annunciating devices, a source of current common to said individual devices, circuit controlling mechanism for the passengers upon the floors of the building whereby current is caused to pass through said annunciating devices, and suitable means including for each annunciating device a device operable independently of the passenger, whereby the passage of current through said annunciating devices may be broken.

35. A multiple car elevator signal system comprising a calling device for each floor constructed, connected and arranged to be operable by a waiting passenger, combined with a signaling means constructed, located and adapted to be controlled as the result of such operation and to be noted by the conductor of each of several cars after the passenger has initiated his operation, together with means including a device inaccessible to the passenger and acting to restore the normal conditions without the coöperation of each conductor.

36. A multiple car elevator signal system comprising a calling device for each floor constructed, connected and arranged to be operable by a waiting passenger combined with a signal constructed, arranged and adapted to be controlled as the result of such operation and to be noted by the conductor of one of several cars, together with two or more devices inaccessible to the passenger and constructed and arranged so that either may be operated and will then contribute in the restoration of the normal conditions.

37. A multiple car elevator signal system comprising a calling device for each floor constructed and arranged to be operable by a waiting passenger, combined with a signal controlled by such operation and constructed and adapted to have its operation noted by the conductor of one of several cars, together with means for restoring the normal conditions without the coöperation of the passenger or the conductors of other cars and including a part controllable in the routine working of the said car.

38. A multiple car elevator signal system comprising a calling device on a floor constructed and arranged to be operable by a waiting passenger combined with as many signals as there are cars, suitable circuit connections all constructed and arranged so that each device, if operated, will produce a signal corresponding to each of the cars after the passenger has initiated his operation, together with means for simultaneously restoring the normal conditions of the respective signals.

39. A multiple car elevator signal sys-

tem comprising a calling device on a floor constructed and arranged to be operable by a waiting passenger, combined with as many signal-receiving devices as there are cars, suitable circuit connections all constructed and arranged so that each floor device, if operated, will produce a signal corresponding to each of the cars after the passenger has initiated his operation, and a signal device controlling the restoration of the normal condition of all the parts.

40. A multiple car elevator signal system comprising a calling device on each floor, a signal controllable by one or the other of these for notifying the conductor of a car before his car has reached the calling floor, and a device outside of that car and operated in the routine working of an associated car and constructed and arranged so that, if operated, it will nullify the operation of the signal to the first car.

41. A multiple car elevator signal system comprising an up and a separate down calling device on each floor, means controllable by one or the other of these for notifying a conductor of the call before his car has reached the calling floor, and as many devices as there are cars, each constructed and arranged so that, if operated, it will nullify the operation of the call or signal.

42. A multiple car elevator signal system comprising an up and a separate down calling device on each floor, means controllable by each of these for notifying a conductor of the call before his car has reached the calling floor, and devices corresponding to each car constructed and arranged so that either will nullify the operation of the call or signal as to its own as well as the other cars.

43. A multiple car elevator signal system comprising a separate up and down call for each floor, and in each car a device responsive to both the up and down calls.

44. A multiple car elevator signal system, comprising up and down call devices on the floors, and for each car conductor indicating means responding to either the up or the down call and so arranged in connection with the other parts of the system as to enable him to distinguish between the up and the down calls for a floor, together with a general signal receiving device responding to both up and down calls.

45. A multiple car elevator signal system comprising a signal in a car, a suitable source of current and circuit system, means on a floor for giving a call and initiating a change in the normal condition of the circuit system which controls the signal in the car, means for maintaining such altered circuit conditions and controlling the operation of the car signal after the cessation of the initiating act, combined with devices

equal in number to the cars and each constructed so that, if operated, it will restore the normal conditions.

46. A multiple car elevator signal system comprising an up-down call controlling device on each floor and a signal for each car controllable by the floor device of a floor and each suitably located for observation by the conductor of the corresponding car, together with means including a device constructed and arranged to control at the will of the conductor of a second car whether or not said first conductor may receive the signal controlled by an actuation of a given floor device.

47. A multiple car elevator signal system comprising an up and a down call device on each floor, and on each car a signal device constructed and arranged to be responsive to both the up and down calls from all of the floors, together with suitable circuit connections.

48. A multiple car elevator signal system comprising an up and down call device on each floor, and in each car a signal adapted to be operable as the result of the operation of a floor device, together with devices corresponding to each car, and circuit connections leading therefrom, whereby each of these devices is operable, to prevent the operation of such car signal.

49. A multiple car elevator signal system comprising a calling device on each floor, suitable circuit arrangements between these devices and the car signals, and in each car a signal for noting which floor was called, together with a second device responsive whenever any floor device has operated.

50. A multiple car elevator signal system comprising a calling device on each floor operable by a waiting passenger as the first step in signaling; a magnet constructed and operating to contribute in the restoration of the normal conditions; a signal on a car constructed, connected and adapted to indicate the corresponding floor call, and a device operated in the routine working of another car and acting to control the magnet in the restoration of the normal conditions.

51. A multiple car elevator signal system comprising a calling device on a floor constructed, connected and arranged so that a waiting passenger may originate a call; a signal on a car responsive to the call, and means for terminating the signal independently of the specific operation of the passenger or of the conductor of that car, together with a device controllable by the conductor of a second car and also adapted, if operated, to terminate the signal on the first car.

52. A multiple car elevator signal system comprising separate up and down calls on a floor, and means operating to notify the conductor whether the up or the down call

has been operated and including a device in the car and a wire in circuit for the up as well as the down call, and a switch outside of the car in circuit with these calls and constructed and adapted to terminate the call.

70

53. A multiple car elevator signal system comprising an up and down signal controlling apparatus at a floor, and means including as many separate elements as there are cars co-operating in notifying the conductor of the first available car that passes in the direction indicated to stop as the result of the notification.

75

54. A multiple car elevator signal system, comprising an up and a down signal controlling apparatus at a floor, and means including as many separate elements as there are cars co-operating in notifying the conductor of the first available car that passes in the direction indicated to stop as the result of the notification, together with means—including as many devices as there are cars—each constructed and operable to cause the restoration of the normal conditions by the operation of one of such devices.

80

55. A multiple car elevator signal system, comprising an up and a down signal controlling apparatus at a floor, and means including for the up as well as for the down as many separate elements as there are cars, co-operating in notifying the conductor of the first available car that passes in the direction indicated to stop as the result of the notification.

95

56. A multiple car elevator signal system, comprising an up and a down signal controlling apparatus at a floor, and means including for the up as well as for the down as many separate elements as there are cars co-operating in notifying the conductor of the first available car that passes in the direction indicated to stop as the result of the notification, together with means—including as many devices as there are cars—each constructed and operating to cause the restoration of the normal conditions by the operation of one of such devices.

100

57. A multiple car signal system, comprising an up and a down signal controlling apparatus at a floor, signal receiving means on each floor, and, corresponding to the signal receiving means, as many switch contacts as there are cars constructed and connected to control the respective floor signal-receiving means; together with a signal receiving device for each car.

115

58. A multiple car elevator signal system comprising means constructed and arranged to enable a waiting passenger to signal the first available car to stop for him, and including signal calling devices for up and down calls, respectively, a source of current normally not in action, a signal device for each car, connections between these devices and the current source, means

120

125

130

controlled by the floor devices for enabling the current source to operate the signal devices, and devices constructed and operating to maintain such altered conditions of the current source after the cessation of the act of the passenger.

59. A multiple car elevator signal system, comprising an up and a down signal controller at a floor and constructed and arranged to be operated by a passenger to govern a current flow, and, on a car, a car signal constructed and arranged to appear and to disappear in accordance with the presence or absence of current flow, together with means including a device operable independently of any subsequent act of the passenger for restoring the normal current conditions and thus terminating the control initiated by that act of the passenger.

60. An elevator signal system comprising at each of several floors normally open circuits, a calling device having terminals constructed and arranged to close said circuits and operable by a passenger for up and down calls, respectively, together with a return signal receiving device on the floor constructed and arranged to operate only if the call on the floor has been operated.

61. A multiple car elevator signaling system, comprising a device constructed and adapted to be noted as a signal by the operator of a car, a circuit controlling device on a floor constructed and adapted to control the said signal and operable by a waiting passenger, together with means for maintaining such control after the cessation of the act of the passenger and for terminating it.

62. In electric signaling apparatus for elevators, the combination of two groups of individual electric lamps in each of two cars, one group serving for "up" signal purposes and the other group serving for "down" signal purposes, and both grouped within the car, electric circuits wherein said lamps are placed, said circuits comprising individual wires leading to the corresponding lamps, and a return wire common to the lamps of one car, a source of current common to said individual lamp circuits, push-button or like circuit controlling mechanism upon the floors of the building whereby current is caused to pass through said lamps, and suitable means whereby the passage of current through said lamps may be interrupted.

63. In electric signaling apparatus for elevators, the combination with two groups of individual annunciating devices located in each of two or more cars, one group serving for up signal purposes and the other group serving for down signal purposes and both grouped within the car, electric circuits wherein said devices are placed, said circuits comprising individual wires leading to the

corresponding annunciating devices, and a return wire common to several of said devices, a source of current common to said individual devices, push-button or like circuit controlling mechanism upon the floors of the building and controlling the individual devices of both of the cars—whereby current is caused to pass through said annunciating devices, and suitable means whereby the passage of current through said devices may be broken.

64. A multiple car elevator signal system comprising an up and down button on each floor, a signal receiving device in each car, a source of current normally open and adapted, when closed, to control the same, a pair of contacts for the up and down call devices, respectively, of each floor, a separate line for each of such devices, and for each such floor device a magnet contributing in maintaining the closed circuit condition of the line; together with an answer-back signal receiving device for each up and down button, the same being located on the floors, and means constructed and arranged so that there will be a coördinate actuation of this answer-back device and termination of the closed circuit condition corresponding to the signal from a given floor.

65. At each of several floors, a calling device operable for up and down calls, respectively, and up and down signal receiving devices constructed and arranged to operate as answer-back signals for the floor and so operable only if the call corresponding thereto on the floor has been operated, signal receiving devices constructed and arranged to be operable by the calls so that the conductor may note the same, combined with means including a switching device corresponding to the car for causing the signal given to the car to be terminated simultaneously with the operation of the answer-back device on the floor.

66. A multiple car elevator signal, including an up and down call on each floor, signal receiving mechanism in more than one car, an answer-back device for each call, a movable part corresponding to each car and operable to terminate the call and also to operate the answer-back and suitable connections whereby such operation will restore the normal condition as to all other cars.

67. A multiple car elevator signal system comprising means constructed and arranged to enable a waiting passenger to notify the first available car to stop for him and including a calling device for the up and another for the down calls, an independent wire leading from each floor to a stationary point in the building, a signal receiving device in each car, a movable wire to the signal receiving device in each car; magnets, each contributing in the termination of the signal for that floor; a switching device corre-

5 sponding to each car and so organized with respect to the said magnet that the operation of the switch device corresponding to either car will affect the said magnet and contribute in terminating the corresponding act of signaling initiated by the waiting passenger.

68. A multiple car elevator signal system comprising a suitable calling device located at each floor, means governed by the calling 10 devices and constructed and arranged to enable a waiting passenger to specify to the conductor of the first available car his floor and desired direction of travel, before or upon reaching the floor specified; means for 15 nullifying that as to other cars, and means for enabling subsequent passengers to repeat the operation independently.

69. A signaling system comprising circuit closing controllers at sub-stations, an independent line for each to two or more central station organizations at each of which is an annunciator comprising a group of independent lamps representing the respective stations, and an additional device constructed to respond as long as any sub-station controller is in operation, together with two groups of switches each group corresponding to an annunciator and the switches corresponding individually to the 30 lamps and each switch adapted to extinguish the corresponding lamp at the other annunciator, combined with a single source of current for the entire system and with means for automatically continuing the circuit closure of a sub-station controller after the act 35 of control has been initiated and for terminating it by the actuation of the corresponding switch at either of the annunciator stations.

70. A signaling system comprising circuit closing controllers at sub-stations, an independent line for each to two or more central station organizations at each of which is an annunciator comprising a group of lamps 40 representing the respective stations, and an additional device constructed to respond as long as any sub-station is in operation, together with two groups of switches each group corresponding to an annunciator and the switches corresponding individually to the 45 lamps and each switch adapted to extinguish the corresponding lamp at both annunciators, combined with a single source of current for the entire system and with means for automatically continuing the circuit closure of a sub-station controller after the act 50 of control has been initiated and for terminating it by the actuation of the corresponding switch at either of the annunciator stations.

71. An annunciator comprising a group of lamps, a common source of current for the same and out-going lines which lead to sub-stations, and for each lamp and in circuit 55 connection therewith, a contact, a magnet

and an armature constructed, connected and arranged to coöperate in the extinguishing of the lamp corresponding thereto, the said magnets being, respectively, located in said lines.

72. Two annunciators, each comprising a group of lamps, a common source of current for the same and out-going lines which lead to sub-stations, and for each lamp of one of the annunciators and in circuit connection therewith a contact, a magnet and an armature constructed, connected and arranged to coöperate in the extinguishing of the lamp corresponding thereto, the said magnets being, respectively, located in said lines the corresponding lamp in each annunciator being controlled by the same outgoing line.

73. Two annunciators, each comprising a group of lamps, a common source of current for the same and out-going lines which lead to sub-stations, and for each lamp of one of the annunciators and in circuit connection therewith a contact, a magnet and an armature constructed, connected and arranged to coöperate in the extinguishing of the lamp corresponding thereto, the said magnets being, respectively, located in said lines, the corresponding lamps in the two annunciators being connected to the same outgoing line and in series with each other.

74. An annunciator comprising a group of lamps, a common source of current for the same and out-going lines which lead to sub-stations, and for each lamp and in circuit connection therewith a contact, a magnet and an armature constructed, connected and arranged to coöperate in the extinguishing of the lamp corresponding thereto, the said magnets being located respectively in said lines, together with means including a switch corresponding to each lamp whereby any lamp may be restored independently of any other lamp in the annunciator and independently of the operator at the annunciator.

75. At each of several sub-stations, a movable device constructed and adapted, when moved, to control the flow of current, a common source supplying such flow, an independent line from each such station to a central station; at this station an annunciator consisting of a group of lamps fed from said single source and arranged to indicate by their condition the position of the respective sub-station elements, together with a group of controlling elements or switches in proximity to the lamps and arranged, respectively, in corresponding order, and each constructed and adapted, when controlled by the operator at the central station, to participate in affecting the operation of the lamp and suitably responsive mechanism at the corresponding sub-station also affected by the control of the corresponding switch.

125
130

76. At each of several sub-stations, a movable device constructed and adapted, when moved, to control the flow of current, a common source supplying such flow, an independent line from each such station to a central station; at this station an annunciator consisting of a group of lamps fed from said single source and arranged to indicate by their condition the position of the respective sub-station elements, together with a group of controlling elements or switches in proximity to the lamps and arranged, respectively, in corresponding order, and each constructed and adapted, when controlled by the operator at the central station to participate in affecting the operation of the lamp and suitably responsive mechanism at the corresponding sub-station also affected by the control of the corresponding switch, together with a second group of similarly arranged switches under control of a second operator, connections whereby each such switch is arranged to control the same line as the corresponding switch under control of the first operator.

77. At each of a number of sub-stations, a pair of normally separated contacts; suitable circuit connections to a central station at which is an annunciator consisting of a group of lamps corresponding, respectively, to the sub-stations; a source of current common to the sub-station contact pairs; means whereby the lamp corresponding to any given substation operates upon the effective joinder of the corresponding sub-station contacts; and a common wire feeding the group of lamps, together with a magnet, an armature, and an additional element for each circuit arranged to contribute in terminating the joinder of their corresponding pair of contacts.

78. At each of a number of sub-stations, a pair of normally separated contacts; suitable circuit connections to a central station at which is an annunciator consisting of a group of lamps corresponding, respectively, to the sub-stations; a source of current common to the sub-station contact pairs; means whereby the lamp corresponding to any given substation operates as the result of the effective joinder of the corresponding sub-station contacts; and a common wire feeding the group of lamps, together with a magnet and armature representing each lamp and brought into action by the common source of current upon the joinder of said sub-station contacts and participating in controlling the continuance of the operation of the lamp.

79. The combination of several central office or station apparatus, each under control of a different operator; one of these comprising an annunciator consisting of a group of lamps, each representing a given

independent outgoing line; a common source of current for the group of lamps; and at each central apparatus a group of individual switches representing, respectively, said outgoing lines and organized, when actuated by their respective operators, to control the corresponding one of said lines and simultaneously to control the restoration of the normal conditions of the lamp corresponding to the line so controlled.

80. The combination of several central office or station apparatus each under control of a different operator; each of such apparatus comprising an annunciator consisting of a group of lamps each representing a given independent outgoing line; a common source of current for the group of lamps; and at each central apparatus a group of individual switches representing, respectively, said outgoing lines and organized, when actuated by their respective operators, to control the corresponding one of said lines and simultaneously to control the restoration of the normal conditions of the lamp corresponding to the line so controlled.

81. At each of a number of sub-stations, a pair of normally separated contacts; suitable circuit connections to a central station, an annunciator at said station consisting of a group of lamps, each lamp corresponding to one sub-station; a source of current common to the sub-station contact pairs; means whereby the lamp corresponding to any given sub-station operates as the result of the effective joinder of the corresponding sub-station contacts; and a common wire feeding the group of lamps; a circuit controlling switch for each circuit, under the control of the operator at the annunciator station and being independently operable to control the extinguishment of the lamp corresponding to an operated sub-station and at the same time to control the corresponding sub-station line.

82. At each of a number of sub-stations, a pair of normally separated contacts; suitable circuit connections to a central station, an annunciator at said station consisting of a group of lamps, each lamp corresponding to one sub-station; a source of current common to the sub-station contact pairs; means whereby the lamp corresponding to any given sub-station operates as the result of the effective joinder of the corresponding sub-station contacts; and a common wire feeding the group of lamps; a circuit controlling switch for each circuit, under the control of the operator at the annunciator station and being independently operable to control the extinguishment of the lamp corresponding to an operated sub-station and at the same time to control the corresponding sub-station line; together with a second contact switch for each circuit, these

second switches being grouped under the control of a second operator and connections whereby each such switch is arranged to be by him independently operable to control the corresponding sub-station line.

5 83. At each of a number of sub-stations, a pair of normally separated contacts; suitable circuit connections one for each pair of contacts to two annunciator stations, an 10 annunciator at each of said stations consisting of a group of lamps, each lamp corresponding to one sub-station; a source of current common to the sub-station contact pairs; means whereby each lamp corresponding 15 to any given sub-station lights as the result of the effective joinder of the corresponding sub-station contacts; and a common wire feeding a group of lamps; a circuit controlling switch for each circuit, under 20 the control of the operator at each annunciator station and independently operable to extinguish the corresponding lamp and also to control the corresponding sub-station line, together with adjunctive and electrically controlled means coöperating with 25 the switches whereby after the lighting of the lamp the operator at either annunciator station can discover whether the other has operated the switch corresponding to such 30 sub-station.

84. At each of a number of sub-stations, a pair of normally separated contacts; suitable circuit connections to a central station, an annunciator at said station consisting of 35 a group of lamps, each lamp corresponding to one sub-station; a source of current common to the sub-station contact pairs; means whereby the lamp corresponding to any given sub-station lights as the result of 40 the effective joinder of the corresponding sub-station contacts; and a common wire feeding the group of lamps; a circuit controlling switch for each circuit, under the control of the operator at the annunciator 45 station and independently operable to extinguish the corresponding lamp and at the same time to control the corresponding sub-station line, and a magnet at the sub-station constructed and arranged to coöperate 50 with the normally separated contacts thereat in such manner that it may be caused to control their re-opening after the operator at the annunciator station has controlled the line.

55 85. At each of a number of sub-stations, a pair of normally separated contacts; suitable circuit connections to a central station, an annunciator at said station consisting of a group of lamps, each lamp corresponding 60 to one sub-station; a source of current common to the sub-station contact pairs; means whereby the lamp corresponding to any given sub-station lights as the result of the effective joinder of the corresponding 65 sub-station contacts; and a common wire

feeding the group of lamps; a circuit controlling switch for each circuit, under the control of the operator at the annunciator station and independently operable to extinguish the corresponding lamp and at the same time to control the corresponding sub-station line; and a magnet at the sub-station associated with the normally separated contacts thereat and so constructed and arranged that it may be caused to control their re-opening as the result of operation from the annunciator station.

86. In electric signaling apparatus for elevators, the combination with two series of individual electric lamps, one series serving for "up" signal purposes, and the other series serving for "down" signal purposes and both grouped within the car, electric circuits wherein said lamps are placed, said circuits comprising individual wires leading to the corresponding individual lamps and a return wire common to all of said lamps, a source of current common to said individual lamp circuits, push button or like circuit-controlling mechanism upon the floors of the building whereby current is caused to pass through said lamps, and suitable means whereby the passage of current through said lamps may be broken.

87. At each of several sub-stations, a movable device constructed and adapted, when moved, to control the flow of current, a common source supplying such flow, an independent line from each such station to a central station; at this station an annunciator consisting of a group of lamps fed from said single source and arranged to indicate by their condition the position of the respective sub-station elements, together with a group of controlling elements or switches in proximity to the lamps and arranged, respectively, in corresponding order, and each constructed and adapted, when controlled by the operator at the central station to participate in affecting the operation of the lamp and suitably responsive mechanism at the corresponding substation also affected by the control of the corresponding switch and including means constructed, arranged, and operating when controlled by the receiving operator to participate in terminating the flow of current initially controlled at the substation.

88. At each of several sub-stations, a movable device constructed and adapted, when moved, to control the flow of current, a common source supplying such flow, an independent line from each such station to a central station; at this station an annunciator consisting of a group of lamps fed from said single source and arranged to indicate by their condition the position of the respective sub-station elements, together with a group of controlling elements or switches in proximity to the lamps and arranged, re-

spectively, in corresponding order, and each constructed and adapted, when controlled by the operator at the central station to participate in affecting the operation of the 5 lamp, and suitably responsive mechanism at the corresponding sub-station also affected by the control of the corresponding switch together with a second group of similarly arranged switches under control of a second 10 operator, connections whereby each such switch is arranged to control the same line as the corresponding switch under control of the first operator, the responsive mechanism at the substation including means 15 constructed, arranged and operating when controlled by the receiving operator to participate in terminating the flow of current initially controlled at the substation.

89. At each of several sub-stations, a movable device constructed and adapted, when moved, to control the flow of current, a common source supplying such flow, an independent line from each such station to a central station; at this station an annunciator consisting of a group of lamps fed from said single source and arranged to indicate by their condition the position of the 25 respective sub-station elements, together with a group of controlling elements or 30 switches in proximity to the lamps and arranged, respectively, in corresponding order, and each constructed and adapted, when controlled by the operator at the central station to participate in affecting the operation 35 of the lamp and suitably responsive mechanism at the corresponding sub-station also affected by the control of the corresponding switch, and including an element adapted to be first moved by the sub-station 40 operator, and a magnet constructed and operating when controlled from the receiving station to control a subsequent motion of said element.

90. At each of several sub-stations, a movable device constructed and adapted, when moved, to control the flow of current, a common source supplying such flow, an independent line from each such station to a central station; at this station an annunciator consisting of a group of lamps fed from said single source and arranged to indicate by their condition the position of the 45 respective sub-station elements, together with a group of controlling elements or 50 switches in proximity to the lamps and arranged, respectively, in corresponding order, and each constructed and adapted, when controlled by the operator at the central station to participate in affecting the operation 55 of the lamp, and suitably responsive mechanism at the corresponding substation also affected by the control of the corresponding switch together with a second group of similarly arranged switches under 60 control of a second operator, connections

whereby each such switch is arranged to control the same line as the corresponding switch under control of the first operator the responsive mechanism at the sub-station including an element adapted to be first moved by the substation operator, and a magnet constructed and operating when controlled from the receiving station to control a subsequent motion of said element. 70

91. A multiple car elevator signal system comprising a call device on each floor, in each car an annunciator with an element corresponding to each floor call device and constructed to show simultaneously upon the actuation of any given floor call means for continuing this display after the cessation of the actuation by the passenger whereby the passenger is enabled to summon the most available car to stop for him, together with means for simultaneously restoring the corresponding element in all cars without affecting elements corresponding to other floor calls, said means including as many devices each suitable for this purpose as there are cars, each conveniently located so that it may be actuated by the conductor who stops at the calling floor. 80 85 90

92. A multiple car elevator signal system comprising means for initiating an up or down call from a floor, answer-back signal receiving means on that floor operable only if the corresponding call has been initiated, and constructed and arranged to indicate that the call is being received, together with organizations of circuits and mechanisms corresponding in number to the cars and each including means adapted, if operated, for receiving and terminating such call and for operating the corresponding answer back signal. 95 100 105

93. A multiple car elevator signal system comprising means for initiating an up or down call from a floor, answer-back signal receiving means on that floor operable only if the corresponding call has been initiated, 110 and constructed and arranged to indicate that the call is being received, as many sets of restoration controlling devices as there are cars, each set comprising an element corresponding to an answer-back signal 115 whereby on each floor the answer back device may be operated by way of the corresponding element of whatever set is used for that purpose.

94. A multiple car elevator signal system 120 comprising a call device on each floor, in each car an annunciator with an element corresponding to each floor call device and constructed to show simultaneously upon the actuation of any given floor call; means 125 for continuing this display after the cessation of the actuation by the passenger whereby the passenger is enabled to summon the most available car to stop for him, together with means for coördinately re- 130

storing the corresponding element in all cars without affecting elements corresponding to other floor calls, said means including as many devices, each suitable for the 5 purpose as there are cars.

95. An elevator signal system comprising, in combination with a suitable current source and connections, a signal-receiving device suitably located for observation by 10 the conductor of a car and constructed, arranged and adapted, unless prevented, to indicate in a recognizable manner that the conductor of that car is to stop at a floor during a trip in the proper direction in 15 response to an up or down call from said floor; similar receiving devices corresponding to each of the other cars; means including a device suitably located and organized to be operable in the routine working of 20 another car and adapted, if operated, to prevent such indication for the first car; at each floor an up or down call initiating device operable by the passenger from one location irrespective of the number of cars 25 so equipped and controllable; all coöperating so that the act of the passenger will direct the attendance of the conductor of the first available car.

96. An elevator signal system comprising, 30 in combination with a suitable current source and connections, a signal receiving device suitably located for observation by the conductor of a car and constructed, arranged and adapted, unless prevented, to indicate in a recognizable manner that the conductor of that car is to stop at a floor during a trip in the proper direction in 35 response to an up or down call from said floor; similar signal receiving devices correspond-

ing to each of the other cars; means including a device suitably located and organized to be operable in the routine working of another car and adapted, if operated, to prevent such indication for the first car; said device being suitably located for operation by the conductor at will and suitably arranged so that he may control whether or not the conductor of the other car shall receive such signal; at each floor an up or 40 down call initiating device operable by the passenger from one location irrespective of the number of cars so equipped and controllable; all coöperating so that the act of the passenger will direct the attendance of the conductor of the first available car. 45

97. A multiple car elevator signal system comprising adjunctive parts and on a floor for a car suitably located for observation by the conductor thereof, a signal receiving 50 device constructed and arranged to be controllable by the floor device; means for maintaining a change in the normal condition of the system initiated by the actuation of the floor device; and corresponding 55 to that car and also to another car and suitably located and arranged to be actuated in the routine working of either car a restoration controlling device constructed and arranged so that if actuated either will contribute in restoring the normal conditions of the system for that call. 60

In witness whereof I have signed this specification in the presence of two witnesses.

F. BENEDICT HERZOG.
